PORATION OF NEW YORK

APPARATUS FOR RECOVERING AND CONTROLLING THE FLOW OF OIL IN
REFRIGERATING SYSTEMS

Application filed July 7, 1930. Serial No. 466,055.

This invention relates to apparatus for recovering and controlling the flow of oil in refrigerating systems, and has to do more particularly with novel positive acting means

5 for returning oil from the boiler of a flooded type lowside.

In refrigerating systems wherein the oil is allowed to circulate more or less through the system, it is obvious that some of the oil 10 in the crank case of the compressor is pumped over into the evaporator along with the refrigerant. Some provision, therefore, has to be made for the recovery of this oil as otherwise the crank case of the compressor will 15 eventually run dry or substantially dry. Heretofore, provision has been made for returning the oil from the surface of the liquid refrigerant but a great objection to such systems has been the tendency of the refrigerant 20 to be taken into the suction line when the refrigerant is boiling during the operating cycle. This taking of the refrigerant into the suction line results in expanding of the refrigerant and frosting back between the 25 evaporator and the compressor.

It is the object of the present invention to provide means for positively separating the oil from a refrigerant, or the invention can be better explained as relating to a method 30 of purifying the oil and separating the refrigerant therefrom and then returning it to the compressor regardless of the position of the compressor with respect to the evaporator or the condition of the oil in the evaporator. In this case the gist of the operation 35 is the segregating of a certain portion of the top layer of the liquid and the positive removal of any entrapped refrigerant.

Another important step in the method resides 40 in the utilizing of the segregated body of liquid to precool the incoming relatively warm refrigerant. This is accomplished by providing a baffle plate or a chamber for separating the mixed oil and refrigerant from 45 the main body of refrigerant and arranging this baffle plate or chamber adjacent the incoming refrigerant conduit. A still further feature has to do with the provision of novel means for withdrawing the oil from the chamber 50 formed by the baffle plate, irrespective

of the position of the compressor. In this case use is preferably made of a Venturi tube arrangement operated by the flow of refrigerant gases to the compressor.

In the drawings:

Fig. 1 is a longitudinal section, partly cut away, of a flooded type evaporator provided with our novel baffle plate structure and forming a chamber around the refrigerant inlet conduit.

Fig. 2 is a sectional view taken on line 2—2 of Fig. 1 and illustrating one form of header and service valve structure that may be used in exemplifying the present invention.

Fig. 3 is a front elevation of a preferred 65 form of baffle plate structure.

Fig. 4 illustrates a modified manner of securing the inlet valve to the float control arm.

Fig. 5 is a side view partly in longitudinal section of a modified arrangement of baffle 70 plate structure in combination with a Venturi tube refrigerant control.

Fig. 6 is a view similar to Fig. 5 but showing our novel evaporator unit as used in connection with a high side float.

One of the primary purposes of the present invention is the provision of an auxiliary reservoir or chamber for segregating a limited portion of the oil and combined refrigerant from the surface of the liquid in the evaporator. In Fig. 1 this reservoir is generally designated as at 1 and is formed by providing an annular recess 2 in the header member 3 and by providing a baffle plate 4 for generally separating the main body of refrigerant in the 85 evaporator from this auxiliary reservoir 1.

In the embodiment shown in Fig. 1 the evaporator may be generally designated 5 and the float therefor as at 6. The evaporator may be provided with any suitable header 90 construction and suitable service valves as best shown in Fig. 2. The inlet service valve may be generally designated 7 and the outlet service valve 8.

The inlet service valve may be connected 95 by means of a suitable passageway to a central aperture 9 which constitutes the inlet conduit for the refrigerant. The inlet conduit may terminate in a suitable projection 10 as best shown in Fig. 1 and the flow of 100

refrigerant through this conduit may be regulated by means of a suitable valve member 11 freely carried by means of a pin 12 secured to the arm of the float 6.

5 The top portion of the baffle plate 4 is preferably embossed so as to provide a projection 13 which serves as a passageway for the evaporated refrigerant. One or more apertures 14 are preferably formed in the baffle plate as 10 best shown in Fig. 3, so as to normally allow a portion of the oil or combined oil and refrigerant, at the surface of the body of liquid in the evaporator, to flow into the reservoir 1.

15 In systems where the oil is lighter than refrigerant it will naturally rise to the top of the body of liquid in the evaporator and will, during the operating cycle, have considerable refrigerant mixed therewith. A portion of this oil or mixed oil and refrigerant will be 20 collected in the reservoir 1 and subjected to the heat of the incoming refrigerant passing through the conduit 10. This heat will assist in causing the refrigerant mixed with the oil to evaporate and pass off as evaporated 25 refrigerant through the exhaust valve 8 in the usual manner. The incoming refrigerant passing through the conduit 10 will, of course, give up its heat to the expanding refrigerant within the reservoir and will be 30 materially cooled which will greatly increase the efficiency of the system. The separated oil in the reservoir 1 will readily be drawn into the exhaust conduit in the natural operation of the system.

35 Fig. 4 illustrates a modified manner of securing the valve member 11 to the float arm. In this embodiment two apertures 15 and 16 are formed in the hollow arm and positioned so as to be out of alignment. A suitable pin 17 may then be driven through said apertures 15 and 16 so as to distort the pin and secure the same in place. It will be obvious that a certain amount of resiliency will then be given to the valve plunger.

45 In Fig. 5 we have shown a modified manner of arranging the auxiliary reservoir in combination with a Venturi tube member which may be used in connection with the exhaust conduit. This Venturi tube member may be 50 of a construction similar to that disclosed in the application of Ransom H. Beman, Serial No. 421,133, filed January 16, 1930. The header may be provided with a suitable inlet port 18 and a valve member 19 adapted to receive and cooperate with a valve plunger 12 in the same manner as shown in Fig. 1. A reservoir 20 may be formed in the manner shown and is preferably adapted to carry the float structure in addition to a Venturi tube 55 21 and an exhaust conduit 22. This exhaust conduit 22 is preferably so arranged as to normally serve as a means for removing the evaporated refrigerant.

The reservoir 20 is provided with one or 60 more apertures 23 which are preferably po-

sitioned at a height just above or at the normal level of the liquid in the reservoir. The position of the aperture or apertures 23, may, of course, vary considerably with different types of cooling units. From the neck of the 70 Venturi tube a small tube 24 projects downwardly into the reservoir 20 and preferably to a point somewhat below the oil level hole 23.

75 In operation, when violent boiling occurs within the evaporator or when oil is pumped over to raise the level of the liquid to the oil return hole 23, the oil or a mixture of oil and refrigerant will spill over into the reservoir 20. As this oil or mixture of oil and refrigerant flows into the reservoir, it will be placed in contact with the relatively warm conduit 19 and head member 18 whereby the refrigerant will be evaporated and rise to the surface of the liquid in the reservoir, and if the 85 tube 24 is not submerged it will assist in evaporating the refrigerant from the oil until the residue in chamber 20 contains a small percentage of refrigerant, if any.

90 This relative difference in temperature is caused by the relatively warm compressed liquid refrigerant which is being drawn into the evaporator. Oil gradually accumulates in the reservoir 20 until it reaches the mouth of a small tube 24 from which point it will 95 be sprayed into the exhaust conduit and due to the difference in pressure across the neck of the venturi, this oil will be carried back to the compressor. The upper part of the reservoir 20 may or may not be open as if it is 100 open the expanded refrigerant gases may pass into the upper part of the evaporator and be drawn off in the usual manner or if closed the gases will assist in forcing the relatively pure oil from the top of the reservoir 105 into the Venturi tube.

110 It will be readily understood that the Venturi tube can be designed to take care of various heights of the compressor above the evaporator. In other words, with very small differences in pressure across the Venturi neck it will be possible to draw the oil up to practically any height that the compressor might be positioned above the evaporator. Therefore it will be seen that when the Venturi tube arrangement is used it is immaterial 115 where the compressor is placed with relation to the evaporator to obtain separation and positive return of the oil without causing a frosting back of the exhaust line between the evaporator and compressor.

120 In Fig. 6 we have illustrated the manner of adopting the evaporator and header structure, as shown in Fig. 5, to a refrigerating system of the type having a high side float. It will be understood that the structure illustrated in Fig. 1 may also be utilized in connection with a high side float, the type of structure shown in Fig. 5 being shown merely 125 as one embodiment. In either case, the only 130

difference in the systems is that the float structure instead of being positioned for operating within the evaporator is positioned outside of the same or in what is known as the 5 high side of the system. In illustrating this embodiment we have shown a compressor as at 25, a condenser 26, and a standard form of high side float as at 27. A suitable conduit 28 leading from the high side float is adapted 10 to be connected to the inlet port 18 of the evaporator header, such evaporator header being shown in comparatively enlarged section.

In the operation of the structure and system such as illustrated in Fig. 6, the liquid level to be maintained in the evaporator is predetermined in the usual manner, as by weighing the liquid admitted to the system or by taking in liquid until "frosting back" 15 when a small amount may be discharged. During the operating cycle of the system, it will be obvious that oil will be entrapped and carried over into the evaporator with the refrigerant. In the preferred operation 20 of the system the oil is of such specific gravity that it will collect at the surface of the refrigerant in the evaporator as indicated in the heavy dotted lines in Fig. 6. In most instances such layer of oil will undoubtedly 25 have a fairly high percentage of refrigerant mixed therewith. It will be obvious that during more or less violent agitation of the liquid in the evaporator a certain quantity of the oil and refrigerant will flow through 30 the apertures 23 and into the reservoir 20. As previously explained, the refrigerant within the reservoir 20 will be substantially evaporated out until only oil is left whereby continued operation of the system will cause 35 40 an accumulation of oil in the reservoir 20 until its level reaches and envelopes the port 24, at which time it will be withdrawn through the port back to the compressor so that thereafter there will be a definite flow 45 of oil with a small percentage of refrigerant. As the percentage of refrigerant contained in the oil and reservoir 20 will be relatively low "frosting back" in the return line will not occur. If during any cycle a relatively 50 large amount of refrigerant enters the reservoir 20, it will be lifted or removed by the port 24 until such port is uncovered whereupon the refrigerant will be evaporated and returned as gas through the port until the 55 chamber is again cleared of refrigerant.

What we claim is:

1. Evaporator structure for refrigerating systems comprising means for maintaining liquid within the evaporator at a substantially constant level, a small reservoir formed adjacent the main body of liquid in the evaporator, a baffle plate forming a wall of said reservoir and separating the main body of liquid in the evaporator and the liquid in the 60 reservoir, and one or more apertures in said 65

baffle plate for permitting oil or combined oil and refrigerant to pass into the reservoir.

2. Evaporator structure for refrigerating systems comprising an inlet conduit for incoming liquid refrigerant, a reservoir formed 70 partly by the header part of the evaporator and surrounding said inlet conduit, a baffle plate forming part of said reservoir and separating the liquid in said reservoir from the main body of liquid in the evaporator, said baffle plate being so constructed as to allow a small portion of the surface liquid 75 in the evaporator to be drawn into the reservoir.

3. Evaporator structure for refrigerating systems including an inlet conduit for a liquid refrigerant and an outlet conduit for conducting evaporated refrigerant to the compressor, and comprising a reservoir, a wall for said reservoir having apertures therein 80 and connecting said reservoir with the liquid within the evaporator at a point adjacent the surface thereof whereby oil and mixed refrigerant flow into the reservoir, a Venturi tube connected to the outlet line for conducting refrigerant gases to the compressor unit, and means connecting the neck of the venturi with the top portion of the reservoir for positively withdrawing oil therefrom. 85

4. Evaporator structure for refrigerating systems including an inlet conduit for a liquid refrigerant and an outlet conduit for conducting evaporated refrigerant to the compressor, and comprising a reservoir, a wall for said reservoir having apertures therein 90 and connecting said reservoir with the liquid within the evaporator at a point adjacent the surface thereof whereby oil and mixed refrigerant flow into the reservoir, a Venturi tube connected to the outlet line for conducting refrigerant gases to the compressor unit, and means connecting the neck of the venturi with the reservoir and extending downwardly into the reservoir at a distance below said aperture or apertures. 95

5. Evaporator structure for refrigerating systems of the pipe adapted to receive and maintain liquid refrigerant at a substantially constant level, comprising an auxiliary reservoir for receiving part of the refrigerant, a Venturi tube for conducting away evaporated refrigerant from above the surface of the main body of liquid in the evaporator, and means for connecting a portion of the Venturi tube with said auxiliary reservoir. 110 115 120

In testimony whereof we affix our signatures.
